UNITED STATES PATENT OFFICE.

ABRAHAM KIPP, JR., OF SING SING, NEW YORK.

DESIGN FOR STEAM-ENGINES.

Specification forming part of Design No. **7,916**, dated December 8, 1874; application filed August 4, 1873.
[Term of Patent 14 years.]

To all whom it may concern:

Be it known that I, ABRAHAM KIPP, Jr., of Sing Sing, in the county of Westchester and State of New York, have invented a new and original Design for Steam-Engines, of which the following is a specification:

The nature of my design is fully represented in the accompanying photographic illustration, to which reference is made.

The distinctive features of the design consist mainly in the peculiar configuration given to the single casting constituting the frame, cylinder, guides, plumber-blocks, &c., and their connection with each other, particularly those parts where the branches divide and unite with the opposite pair in the form of an arch, constituting the plumber-blocks or bearings for the crank-shaft, in which configura-

tion the requisite strength, combined with that grace of form and contour arising from its perfect proportion and fitness for the purpose designed, constitutes, together with the working parts of the engine, a design at once adapted to its useful purpose, and one pleasing to the eye and aesthetic taste, at least to that of an engineer or other expert in machinery.

What I claim as my invention is—

The design of the frame of a steam-engine, having the configuration and proportions substantially as shown and described.

ABRAHAM KIPP, JR.
